UNITED STATES PATENT OFFICE

2,337,938

ELECTRIC FUSE

George R. Serfling, Merchantville, N. J., and Carl L. Schuck, Philadelphia, Pa., assignors to General Electric Company, a corporation of New York

Original application September 11, 1941, Serial No. 410,382. Divided and this application August 28, 1942, Serial No. 456,550

1 Claim. (Cl. 200—131)

Our invention relates to electric fuses and particularly to improvements in the construction and method of construction of enclosed high-voltage fuses of the current-limiting type.

This application is a division of our application, Serial No. 410,382, filed September 11, 1941, entitled Electrical fuses and assigned to the same assignee as the present application.

Current-limiting fuses consist in the main of a fusible element in the form of one or more conductors of suitable metal, such as silver or zinc, embedded in a granular inert or refractory arc-extinguishing material of high dielectric strength, such as sand or relatively finely divided quartz. In most of the commercial current-limiting fuses, the conductor or conductors are wound on a suitable supporting core of high temperature resistant ceramic material. To these parts are added an enclosing housing and terminals for the conductors.

The process of assembling current-limiting fuses of this type has heretofore required a large number of steps and it would be desirable to be able to reduce greatly the assembly operations by simplifying the construction with the consequent reduction in cost of such fuses without in any way impairing the operating characteristics thereof.

Accordingly, it is an object of our invention to provide a new and improved fuse construction which not only performs very satisfactorily in every respect but which is simple and rugged in construction and considerably less complicated to manufacture.

It is a further object of our invention to provide a new and improved process for assembling fuses of the current-limiting type.

It is another object of our invention to provide a new and improved fuse construction in which the end cap of the fuse is sealed to the fuse container by molding or die casting a ferrule of metal about one end of the fuse container to form the fuse terminal.

Still another object of our invention is to provide a new and improved means of centering the fuse wire of a current-limiting fuse without the supporting core usually required by the prior-art constructions.

Further objects and advantages of our invention will become apparent as the following description proceeds and the features of novelty which characterize our invention will be pointed out with particularity in the claim annexed to and forming a part of this specification.

For a better understanding of our invention,

reference may be had to the accompanying drawing in which Fig. 1 is a partly sectional view of an exemplary form of current-limiting fuse constructed in accordance with our invention, Fig. 2 is an exploded view of the parts of the fuse shown in Fig. 1, Fig. 3 is a view partly in section to indicate the assembly of the fuse during the manufacturing process, Fig. 4 is an enlarged view of one of the parts of the fuse shown in Figs. 1 to 3, Figs. 5 and 6 illustrate two different steps in the process of manufacturing a current-limiting fuse embodying our invention, and Fig. 7 illustrates a partial sectional view of a fuse device embodying a modification of our invention.

Although, as will be evident to one skilled in the art, certain parts of the present invention may be practiced to advantage with different types and forms of electric fuses, the invention 20 lends itself most advantageously to practice with the enclosed type of fuse, such as is disclosed and claimed in United States Letters Patent No. 2,157,907, granted May 9, 1939, upon an application of K. A. Lohausen, and assigned to the same assignee as the present application, wherein the fusible conductor is shown as being enclosed in a tubular casing of suitable insulating material and surrounded by or embedded in a pulverulent or sandy arc-quenching material.

Referring now to the drawing, we have illustrated an electric fuse device which has a housing structure or casing 10 of open ended tubular form constructed of suitable insulating material, such as glass or fiber. A suitable fuse link, generally indicated at 11, is mounted within tubular casing 10. This fuse link may, if desired, embody the construction disclosed and claimed in the above-mentioned United States Letters Patent so as to include a central section of reduced cross section, thereby providing more satisfactory operation. Although the particular size of cross-section of the fuse wire and the material from which it is made form no part of the present invention, we have found that we obtain very desirable operating characteristics by constructing the fuse link or fusible element 11, best shown in Fig. 2, with an insert 12 of a high resistance wire of suitable cross-sectional area while the two end portions 13 of the fuse link 11 may be formed of a low resistance wire, such as silver, having a somewhat larger cross-section than the insert 12. The insert 12 is maintained in conductive relation with the end sections 13 of fuse 11 by soldering or the like as indicated at 14.

The ends of the fusible element 11 are prefer-

ably looped or folded back upon themselves for a short distance and twisted as indicated at 15, and each of these twisted portions is bent in the form of a U which has a central portion 16 of a length substantially equal to one half the outside diameter of tubular housing or casing 10 as will be described in greater detail hereinafter.

In order to maintain the ends of the fuse link 11 at the central axis of tubular casing 10, we have provided a fuse link attachment plate 17 for each end of tubular housing 10 which includes a small central opening 18 through which the fuse link 11 may extend. Each plate 17 is also provided with a somewhat larger opening 19 through which the tubular casing 10 may be filled with the granular arc-quenching material after the fuse link 11 is supported therein as shown in Fig. 3.

We have discovered that the central core usually required for centering the fuse link in the prior art constructions during the process of filling the tubular casing with the inert granular material may be dispensed with if the fuse link is formed as a helix with the generating radius thereof decreasing near the ends of the fuse link. With such a construction, we have found that, when the fuse link is under a slight tension as in Fig. 3, the tensile forces applied thereto act along the axis of the helix so that the fuse link tends to remain centered within tubular housing 10.

In order to close the open ends of tubular casing or housing 10 after the fuse link and fuse link attachment plates have been assembled, we have provided saucer-shaped end closure members or end caps 20, which are adapted to fit over the ends of tubular casing 10. As shown in the drawing, these end caps are provided with an interlocking means illustrated as an offset shoulder 21 and they are adapted to be held in sealed relationship with tubular casing 10 by metallic ferrules 22 which are molded or die cast around the end of tubular casing 10 so as to envelop the offset shoulder 21 of end cap 20 while permitting the major portion of the end cap to remain exposed. The inherent irregularities of the end caps 20 might be depended upon for obtaining the desired mechanical grip. Accordingly, any suitable end cap with means for obtaining the desired mechanical interlock when such means are enveloped by the die casting material may be employed in accordance with our invention. The die cast or molded ferrules 22 are also cast around the looped end 15 of fuse link 11 which extends outside of tubular casing 10 in the manner shown in Figs. 1 and 3 and, accordingly, provide the terminals for the fuse.

Since the major portion of the end caps 20 remain exposed after the molding or die casting operation, suitable indicia may be provided on this surface of the end caps 20, as indicated in Fig. 4, to set forth the fuse size or any other pertinent information.

The new and improved fuse construction described above permits the number of assembly operations required heretofore in fuses of the current-limiting type to be reduced greatly while, at the same time, eliminating the requirement of a ceramic core and other additional parts. The manufacturing process can now be reduced to a few relatively simple steps, one of which requires the forming of the fusible element or fuse link into the helical form, the generating radius of which decreases near the ends. For the particular fuse link 11 described above in which a more resilient center section 12 is utilized, it is neces-

sary to wind the fuse link on a mandrel 23 shown in Fig. 6 with a reduced central section 24 and tapered end portions 25. The reduced central section 24 is required since the inserted section 12 of the fuse link being more resilient than the end portions must be wound in a smaller diameter helix so that, when removed from the mandrel, the free diameter of the helix composed of the insert will approximate that of the adjacent coils 5 in the end portions (see Fig. 2). The ends of the wire are looped back upon themselves, as indicated at 15 in Fig. 2, and, as was mentioned above, the twisted ends of the fuse link are formed in the shape of a U.

The next step in the process includes the placing of the fuse link in the tubular casing 10 with the fuse link attachment plates 17 seated on either end thereof. The U-shaped ends are constructed with the central portion 16 of the U having a length substantially equal to one half the outside diameter of tubular casing 10 so that the looped end of the fuse link may extend for a short distance down along the outside of tubular casing 10 as best shown in Figs. 1 and 3. The end cap 20 is placed over the lower end of tubular housing 10 so that the structure is assembled as shown in Fig. 3 and is ready for the filling process. Because the fuse link 11 is in the form of a helix, the generating radius of which decreases near the ends, the tensile forces on the ends of the fuse link 11 exerted at the central axis of tubular housing 10 by fuse link attachment plates 17 provide a centering action to maintain the fuse link in the center of tubular casing 10.

In order that the casing may be completely filled with the desired insert granular arc-extinguishing material, the fuse link as assembled in Fig. 3 is preferably mounted on a vibrator 26 of any suitable form, as indicated schematically in Fig. 4, and suitable inert granular material from conduit 27 connected to a suitable source, not shown, is admitted to tubular housing 10 through opening 19 in the upper fuse link attachment plate 17. As soon as the tubular housing 10 is filled with the granular arc-quenching material, the upper end cap 20, which may include any suitable indicia, such as is shown in Fig. 4, is placed over the end of casing 10 and, as shown in Fig. 3, a short portion of each end of fuse link 11 extends along the outside wall of tubular casing 10.

The final step in the assembly of our new and improved fuse construction comprises molding or die casting the ferrules 22 around the ends of tubular casing 10 so as to envelop the interlocking means specifically illustrated as offset shoulders 21 of end caps 20 and hold them in sealed relationship with housing 10 as well as to form good electrical contact with the ends of fuse link 11 protruding out of housing 10 and provide the terminals of the fuse device in a manner well understood by those skilled in the art. The suitable indicia on end caps 20 remain visible after the die casting or molding operation since the major portion of each end cap 20 is exposed and the die cast metal merely grips the interlocking means illustrated as the offset shoulder 21.

Although we have shown a fuse device including an end closure member 20 which is held in place by a molded or die cast ferrule 22, which construction is shown with the looped end 15 of fuse link 11 extending outside of the casing, it should be understood that a molding or die casting operation may be used in which the

metal would flow somewhat inside the casing as shown in Fig. 7, the corresponding parts of which are designated by the same reference numerals as in Figs. 1 and following. In Fig. 7, the tubular casing is provided with an annular recess 10' upon which fuse link attachment plate 17 may be seated. With this arrangement, the end caps 20 may be entirely eliminated and the die cast ferrule 22', as shown in Fig. 7, constructed to surround completely the ends of tubular casing 10" to seal the casing as well as to provide an electrical terminal for the fuse. In this case, the mold for the die casting operation may be provided with suitable indicia so that the desired indicia will appear on the ends of ferrule 22' upon completion of the die casting operation as indicated in Fig. 7.

From the foregoing, it will be seen that the improved fuse construction while being of simple and rugged construction greatly simplifies the manufacturing processes with consequent cost reduction and provides a very satisfactory fuse in every respect.

Although we have elected to describe and illustrate herein a preferred embodiment of our invention as employed in a fuse device as well as the process of construction thereof, it is contemplated that other applications of our invention to fuses or like electrical devices other than the

particular form illustrated will suggest themselves to those skilled in the art. It is intended that such other applications or modifications as do not depart from the true spirit and scope of our invention shall be covered by the appended claim.

What we claim as new and desire to secure by Letters Patent of the United States is.

In a fuse of the current-limiting type, a tubular casing, a body of inert granular refractory arc-quenching material of high dielectric strength contained in said casing, an elongated fusible element embedded in said body of arc-quenching material in said casing, and a molded or die-cast terminal ferrule associated with one end of said casing, said elongated fusible element having an end thereof effectively extending out of said casing so as to be molded into said ferrule and electrically connected therewith, said fusible element being in the form of a helix the generating radius of which decreases near one end thereof so that tensile forces thereon will be transmitted along the axis of the helix and centering of said fusible element while filling said tubular casing with said arc quenching material is obtained.
